TELEVISION SYSTEM

Aldo V. Bedford, Collingswood, N. J., assignor to
 Radio Corporation of America, a corporation
 of Delaware

Application June 9, 1934, Serial No. 729,730

3 Claims. (Cl. 178—7.2)

My invention relates to television systems and particularly to television systems which comprise a cathode-ray transmitter tube and an electric discharge tube generator of deflecting and synchronizing impulses.

It has been found, in television systems utilizing vacuum tube impulse generators, such as generators of the type disclosed in my copending application, Serial No. 726,258, filed May 18, 1934, 10 where pictures are transmitted from a motion picture film, that it is difficult to keep the picture properly "framed". This difficulty is caused partly because of slight variations in the power line frequency, but mainly because of a tendency 15 of the impulse generator frequency to "drift".

I have discovered that the difficulty in keeping the picture framed may be overcome by operating the impulse generator in step or "locked in" with the alternating current power source which 20 supplies power for the film drive.

Operating the impulse generator in step with the power line has a further advantage in that the frequency of the impulse generator output is maintained substantially constant, since the 25 frequency variations of the power line are so slight that it is possible to use a television receiver which does not require a "speed-control" adjustment. In other words, if all substantial drift in the impulse frequency is prevented, there 30 no need for an adjustment on the receiver for changing the frequency of the vertical deflecting oscillator to keep it under the control of the vertical synchronizing impulses.

An object of my invention is to provide an 35 improved television system in which pictures transmitted from a film are properly framed.

More specifically, an object of my invention is to provide a television system, utilizing an electric discharge tube impulse generator, in which 40 pictures transmitted from a film are always properly framed.

A further object of my invention is to provide a television transmitter in which the frequency of an electric discharge tube impulse generator 45 is held substantially constant.

A further and more specific object of my invention is to control the frequency of an electric discharge tube impulse generator with respect to the frequency of the current from a power line 50 or the like.

In one embodiment of my invention, a vacuum tube impulse generator is utilized which has an output suitable for interlaced scanning as described in my above-mentioned copending application. A motion picture film having a pic- 55

ture thereon to be transmitted is moved into position in a film gate by means of a standard intermittent mechanism which is driven by a synchronous motor connected to a 60 cycle power line.

Electrical impulses from the output of the impulse generator and electrical impulses derived from the power line are fed into a common control circuit which changes the frequency of the main oscillator of the impulse generator in response to any phase shift of the impulses in said 10 common circuit.

Other objects, features, and advantages of my invention will appear from the following description taken in connection with the accompanying drawings, in which

Figure 1 is a view of a television transmitter embodying my invention,

Fig. 2 is an end view of a shutter disc shown in Fig. 1,

Fig. 3 is a group of curves which are referred to in explaining my invention,

Fig. 4 is a circuit diagram of an amplifier employed in the system shown in Fig. 1,

Fig. 5 is a set of curves which are referred to in explaining the operation of my control circuit, 25 and

Fig. 6 is a chart illustrating the operation of the picture projector and scanner.

Referring to Fig. 1, a television transmitter system is illustrated which includes a cathode ray transmitter tube 1 of the type described in an article by Dr. V. K. Zworykin which appears in the January, 1934, issue of The Journal of The Franklin Institute. This tube comprises an evacuated envelope 3 having an electron gun 5, 35 a focusing and accelerating anode 7 and a mosaic 9 of light sensitive elements thereon. Deflecting means, such as deflecting coils 11 and 13, are provided for deflecting the electron beam horizontally and vertically, respectively, in order 40 to scan the mosaic 9 with the beam.

To produce the desired current flow through the deflecting coils 11 and 13 for deflecting the electron beam, an electric discharge tube impulse generator is provided. This generator consists 45 of a main oscillator 15 from which are derived electrical impulses of the desired frequency for horizontal deflection and also electrical impulses of the desired frequency for vertical deflection. The main oscillator 15 may be a blocking oscillator 50 consisting of an electrical discharge tube 17 having a cathode 19, a control grid 21 and an anode 23. The control grid 21 is connected through a variable grid leak resistor 25 and through a resistor 27 in the control circuit (which 55

will be described hereinafter) to ground and through ground to the cathode 19.

The anode 23 is maintained at a positive potential by means of a suitable voltage source such as a battery 29 which has its negative terminal connected to the cathode 19 and its positive terminal connected through a resistor 31 and the primary winding 33 of a transformer 35 to the anode 23. A condenser 37 is connected in series with the secondary 39 of the transformer 35, the condenser 37 and secondary 39 being connected between the control grid 21 and the cathode 19. The transformer windings 33 and 39 are so phased that an increase in plate current in the tube 17 causes the control grid 21 to become more positive whereby grid current flows into the grid condenser 37 to charge it in such a direction as to apply a negative bias to the control grid 21. The plate current finally approaches its saturation value so that its rate of increase becomes less, the voltage fed back to the grid decreases whereby the plate current decreases, thus reversing the phase of the voltage applied to the control grid through the transformer 35 and biasing the tube 17 beyond cut-off. During the time the grid has been positive, the condenser has been charged sufficiently to hold the tube biased beyond cut-off and no further oscillation takes place until the charge has leaked off the condenser 37 through the grid leak resistor 25 sufficiently to lower the grid voltage to a value which again permits flow of plate current.

The voltage impulses produced by the oscillator 15 are impressed upon a chain of frequency dividers 41, 43, 45, and 47, each of which may be a blocking oscillator operating the same as the main oscillator 15 but at a lower frequency. Each oscillator is locked in step with the oscillator of next highest frequency. The circuit of the frequency divider 41 is illustrated in order to illustrate the invention more completely but a description of the circuit is not believed to be necessary in view of the description of the main oscillator circuit 15.

The frequency of the main oscillator output is divided in two steps of three and two steps of five, as indicated on the drawings to produce voltage impulses occurring at the rate of 48 per second, this being the desired vertical deflecting or frame frequency. The 48 cycle impulses are supplied to the input circuit of a saw-tooth wave generator 49 which converts them into voltage impulses of the necessary shape for causing a flow of current, having a saw-tooth wave shape, through the deflecting coils 13.

The horizontal deflecting impulses are obtained by impressing a portion of the output energy of the main oscillator 15 upon the input circuit of a frequency divider 51 which divides the frequency of the main oscillator output by two to produce 5400 impulses per second. The output of the frequency divider 51 is impressed upon a saw-tooth wave generator 53 which has its output connected across the horizontal deflecting coils 11 for causing a flow of saw-tooth wave current therethrough.

It will be noted that the vertical deflecting and horizontal deflecting frequencies are such as to cause 112½ lines per picture frame, in order to provide interlaced scanning as described and claimed in my above identified copending application. Although my invention is described in connection with an interlaced scanning system, it should be understood that it is of general application.

My improved television system is especially designed, as will be explained hereinafter, for the transmission of pictures on a motion picture film, such a film being indicated generally at 55. The picture frames are moved intermittently into position in a film gate 57 by means of a standard intermittent 59. The intermittent 59 is driven through a gear box 61 by a synchronous motor 63 at the standard speed whereby 24 pictures per second are projected upon the mosaic 9. A shutter disc 65 is also driven by the synchronous motor 63 through the gear box 61, it being rotated at 24 revolutions per second.

As shown in Fig. 2, the shutter disc 65 has two openings 67 and 69 therein which are diametrically opposite each other for the purpose of cutting off the light projected toward the mosaic periodically, as will be more fully explained hereinafter.

For reasons previously mentioned, and particularly in order to keep the picture properly framed, a control circuit 71 is provided for maintaining the impulse generator locked in with the 60 cycle power line 73 to which the motor 63 is connected. The control circuit includes an electric discharge tube 75 having a cathode 77, a control grid 79 and an anode 81. The tube 75 is so adjusted that it functions as a distorting amplifier or detector. In one specific embodiment this is accomplished by maintaining the control grid 79 at a high negative bias by means of a biasing source, such as a battery 83, the negative bias being high enough to bias the tube beyond the cut-off potential. The anode 81 is maintained at a positive potential by means of a source of potential, such as a battery 85, having its negative terminal connected to the cathode 77 and its positive terminal connected to the anode 81 through the resistor 27. The resistor 27 is shunted by a filter condenser 87.

It will be noted that the resistor 27 is connected in series with the grid leak resistor 25 of the blocking oscillator 15 whereby any change in voltage drop across the resistor 27 causes a change in the bias on the control grid 21 of the blocking oscillator. The filter condenser 87 has sufficient capacity to integrate current impulses and cause a substantially steady flow of current through the resistor 27.

The current flow through the control circuit resistor 27 is caused to vary in response to a phase shift between frequency of the 60 cycle current from the power line 73 and the frequency of the impulse generator output by impressing the impulses from both the power line and the impulse generator upon the input circuit of the control tube 75.

In order to effect the desired control, it is desired, in the specific embodiment illustrated, that the two groups of control impulses occur at the same frequency. Therefore, since current from the power line has a frequency of 60 cycles and the impulses from the vertical deflecting circuit occur at the rate of 48 per second, the 48 cycle impulses are impressed upon a frequency divider 89 which lowers the frequency to 12 impulses per second. The output of the frequency divider 89 is impressed upon a wave shaping amplifier 91 and through a coupling condenser 93 upon the control grid 79 of the tube 75.

Current from the 60 cycle line 73 is impressed upon a frequency divider 95 which divides the frequency by five to produce impulses occurring at the rate of 12 per second. Both the frequency divider 95 and the frequency divider 89

may be blocking oscillators similar to the ones described above. The impulses appearing in the output circuit of the frequency divider 95 are impressed upon a wave shaping amplifier 97 from the output of which they are fed into the input circuit of the control tube 75 through a transformer 99 in such phase that they add with the 12 cycle impulses from amplifier 91.

It should be understood that the wave shaping amplifiers 91 and 97 may be omitted, if desired, particularly when the distorting or detector tube 75 is biased to cut-off, as described. Also, if the power line or other control source provides current at the proper frequency, the sine wave current therefrom may be impressed directly upon the control tube circuit 71 through the transformer 99.

The operation of the control circuit 71 will be better understood by referring to Fig. 3 which shows the wave shape of the voltage impulses appearing in the output circuit of a frequency divider where it is a blocking oscillator. The voltage waves indicated at 101 and 103 are typical of the voltage impulses generated by a blocking oscillator. It will be noted that each wave includes a sharp positive impulse, this impulse being the one which is used for control purposes.

The wave shaping amplifiers 91 and 97 cut off the portion of the voltage wave which appears below the dotted line 105. A preferred circuit for these wave shaping amplifiers is shown in Fig. 4.

Referring to Fig. 4, the amplifier consists of two resistance coupled amplifier stages, the first stage comprising an electric discharge tube 107 which is biased beyond the cut-off potential by means of a biasing battery 109. In the particular embodiment illustrated, the second amplifier stage includes an electric discharge tube 111 which is biased to function as a non-distorting amplifier. The first amplifier stage 107 permits the passage of only the positive peak of the blocking oscillator voltage wave, that is, the portion of the wave above the dotted line 105, while the second stage simply amplifies this impulse and reverses its phase so that it appears in the output of the amplifier 111 as a positive voltage impulse.

The two voltage impulses which are supplied from the wave shaping amplifiers 91 and 97 appear in the input circuit of the control tube 75 as shown at 113 and 115 in view a of Fig. 5. These voltage waves add to give a resultant wave 117 which is shown in view b of Fig. 5.

The grid voltage-plate current characteristic of the tube 75 is shown at 119 in view c of Fig. 5. Following conventional graphical construction, it is seen that the voltage wave 117 impressed upon the input circuit of the tube 75 causes a flow of plate current in the output circuit of the tube which has the wave shape indicated at 121. These impulses 121, which occur in the output circuit of the tube 75 at the rate of 12 per second, charge the filter condenser 87 to produce the substantially steady flow of current through the resistor 27 previously referred to.

Assume that either the frequency of the main blocking oscillator 15 or the frequency of the power line 13 changes to cause the voltage impulses to move farther apart as indicated by the dotted line curve 123 in Fig. 5. The two control impulses now add to give the resultant voltage shown by the dotted line curve 125 in view b of Fig. 5, and this voltage produces a current flow 75 in the output circuit of the control tube 75

which is represented by the dotted line curve 127 in view d of Fig. 5. It is evident that, as a result of the frequency shift, less energy is supplied to the filter condenser 87 and there will be a corresponding reduction in current flow 5 through the resistor 27 whereby the bias voltage on the control grid 21 of the blocking oscillator tube 17 will be changed and the frequency of the blocking oscillator 15 will be corrected.

In order to explain more in detail how the 10 frequency of the blocking oscillator 15 is corrected, it will be assumed that the voltage or control impulses 113 and 115, shown in Fig. 5, are the impulses derived from the power line and from the oscillator, respectively. Also, assume 15 that the oscillator frequency decreases to shift the oscillator control impulse to the position shown by the dotted curve 123. As previously explained, this causes less current to flow through the resistor 27 whereby the negative potential 20 applied to the control grid 21 of the oscillator 15 is decreased to increase the oscillator frequency to its original value. Attention is called to the fact that the oscillator control impulse is not brought back to its original phase relation with 25 the power line control impulse 113; instead, an equilibrium point is reached where a new phase relation between the control impulses causes the proper bias to be applied to the oscillator.

It will be understood that the frequency of 30 the main oscillator 15 may be controlled by the control circuit 71 in various other ways than the particular one illustrated. For example, the voltage drop across the resistor 27 may be utilized to change the potential on the anode 23 of 35 the blocking oscillator tube 17 or it may be utilized to control the voltage on a second grid electrode, not shown. Also, the control impulses applied to the control circuit need not have the same frequency so long as they bear a whole 40 number multiple frequency relation to each other, as in the case of one group of impulses occurring at twice the frequency of the other group.

It will be apparent from the foregoing description that the control circuit 71 and its associated circuits causes the mosaic 9 to be scanned synchronously with the projection of the picture frames thereon. The picture projection and scanning operation is illustrated on the chart in Fig. 6. Starting with the condition just as the 50 shutter opening 67 rotates opposite the picture projector, the picture is projected upon the mosaic 9 at the time A and remains thereon until the time B, at which time the shutter 65 intercepts the beam of light from the projector. 55 During this time, the cathode ray has been brought to its starting position for scanning and the film has been stationary. At the time B, the cathode ray starts scanning the mosaic and completes the scanning at the time C, the film being 60 stationary during this scanning period and there being no light upon the mosaic.

At the time C, the second shutter opening 69 rotates into position opposite the projector to permit the picture to be again projected upon 65 the mosaic until the time D, at which time the light is again intercepted by the shutter 65. At this time, the cathode ray again begins to scan the mosaic 9, the mosaic again being dark. Up to this time, the film has remained stationary. 70

Beginning at the time D, the intermittent 5 starts to move the next picture frame into position. At the time E, the next picture frame has been moved into position and the intermittent stops. The scanning of the dark mosaic con- 75

tinues until the time A, at which time the first shutter opening 57 again moves into position opposite the projector and the second picture frame is projected upon the mosaic.

- 5 The picture signals appear across a resistor 129 connected between the mosaic 8 and the second anode 7 and are impressed upon the picture signal amplifier 131 which amplifies them and impresses them upon a radio transmitter 133 or
10 upon a transmission line (not shown).

In order to maintain the scanning at the receiver synchronized with the scanning at the transmitter, the horizontal synchronizing impulses are impressed through a wave shaping amplifier 135 upon a suitable point in the picture signal amplifier 131. Likewise the vertical deflecting impulses are impressed through a wave shaping amplifier 137 upon a suitable point in the picture signal amplifier 131. Preferably, 15 the horizontal and vertical synchronizing impulses are impressed upon such a stage in the amplifier 131 that they appear at the receiver with a polarity opposite to the polarity of the picture signals in the white direction whereby the synchronizing signals and picture signals may be 20 more easily separated.

The wave shaping amplifiers 135 and 137 may be the same as the amplifier shown in Fig. 4 except that it is preferred to adjust the plate resistor of the first tube such that the signal strength on the grid of the second tube 111 causes the grid to cut off the plate current of the second tube near the peaks of the negative swing. With the wave shaping amplifiers so adjusted, the 25 lower portion of each blocking oscillator impulse is cut off as indicated by the dotted line 105 in Fig. 3 and the peak of the impulses is also cut off by the second amplifier stage 11 as indicated by the dotted line 139. By so shaping the synchronizing impulses before they are impressed upon the picture signal amplifier 131, interference with the picture signals is avoided. It will 30 be understood that in accordance with usual practice, the horizontal synchronizing impulses are transmitted at the end of each scanning line 35 while the vertical synchronizing impulses are transmitted at the end of each picture frame whereby the picture signals and the synchronizing signals are not transmitted simultaneously.

From the foregoing description it will be understood that various modifications may be made in my invention without departing from the spirit and scope thereof and I desire, therefore, that only such limitations shall be imposed thereon as are necessitated by the prior art and set forth in the appended claims.

I claim as my invention:

1. In a television system including a cathode-ray transmitter tube having a mosaic of electron emissive capacity elements therein, means for generating horizontal and vertical deflecting impulses for said tube, said means including an
60

oscillator, means for obtaining a voltage wave from an alternating current source, means for moving a film having a picture thereon to be transmitted, said means including a synchronous motor connected to said source, means for projecting the pictures of said film upon said mosaic, means for obtaining control impulses having a fixed frequency relation to said vertical deflecting impulses, means for impressing said control impulses and said voltage wave upon a common circuit, means for producing a substantially steady current having a value depending upon the phase relation of said control impulses and said wave in said common circuit, and means for controlling the frequency of said oscillator in accordance with the value of said substantially steady current.

2. In a television system including a cathode-ray transmitter tube having a mosaic of electron emissive capacity elements therein, means including an oscillator for generating comparatively high frequency horizontal deflecting impulses and comparatively low frequency vertical deflecting impulses for deflecting the cathode ray in said tube, means for obtaining comparatively low frequency control impulses from said oscillator, means for obtaining periodic voltage pulses from an alternating current power source, means for intermittently moving a film having a picture thereon to be transmitted, said means including a synchronous motor connected to said power source, means for projecting a frame of said film upon said mosaic when said film is stationary, and means for controlling the frequency of said oscillator in accordance with the phase difference of said control impulses and said voltage impulses.

3. In a television system in which a picture is to be projected upon an electron emissive screen surface and in which an electron stream is to be deflected both vertically and horizontally, means for generating horizontal and vertical deflecting impulses for producing said deflection, said means including an oscillator, means for obtaining a voltage wave from an alternating current source, means connected to the power supply for moving a film having pictures thereon with a motion having a predetermined relation to the frequency of said alternating current, means for projecting the pictures of said film upon said screen surface, means for obtaining control impulses having a fixed frequency relation to said vertical deflecting impulses, means for impressing said control impulses and said voltage wave upon a common circuit, means for producing a substantially steady current having a value depending upon the phase relation of said control impulses and said wave in said common circuit, and means for controlling the frequency of said oscillator in accordance with the value of said substantially steady current.

ALDA V. BEDFORD.
